DES. 17

Des. 17

Jordan L. Mott City of New York, N.Y.)
Letters Patent No. 17, dated February 12th 1844
Ante dated Dec. 10th 1843

The Schedule referred to in these Letters Patent and making part of the same. —

To all whom it may concern: Be it known that, Jordan L. Mott, of the City of New York, in the State of New York, have invented and produced a new and original design to be cast in metal, and which I intend to apply, principally, as an ornament to surround a Stove for which I have obtained Letters Patent of the United States, and which I denominate the Galorified Stove, but which ornamental design may, in whole or in part, be applied to stoves of other descriptions. The drawing which accompanies this specification is a representation of my said ornamental design, which may be considered as divided or divisible, into three sections or parts, which I will denominate the lower, the middle, and the upper sections, and these I claim both separately and conjointly, as constituting my said new Design. The part marked A, in the accompanying drawing, is the lower section, or base; the part marked B, the middle section, and the part marked C, the upper section. And in these respective sections I claim the particular manner of forming the ornamental devices as represented on each of them, when such ornamental devices are combined with, and placed upon bodies having the shape and configuration designated and represented in the drawings of the said sections; but I do not claim the individual scrolls, or trifling, things shown, when taken separately, but only as combined, and as constituting such ornamental bodies and sections as are herein fully identified.
